UNITED STATES PATENT OFFICE.

JOSEPH K. DAVISON, OF PHILADELPHIA, PENNSYLVANIA.

DESIGN FOR A BADGE.

SPECIFICATION forming part of Design No. 16,672, dated May 4, 1886.

Application filed February 18, 1886. Serial No. 192,463. Term of patent 14 years.

To all whom it may concern:

Be it known that I, JOSEPH K. DAVISON, a citizen of the United States, residing in the city and county of Philadelphia, State of Pennsylvania, have invented and produced a new and original Design for Badges, of which the following is a specification, reference being had to the accompanying drawing, forming part thereof.

10 The leading feature of my design for a badge is a bar having above the same a scroll and a shield with a monogram pendent from a scroll below the bar.

15 A represents the cross which depends from the ribbon B, and C represents a bar, which, being at the top, has the ribbon attached to it. The peculiar design of the cross is not claimed in the present application. The bar C has on its face space for the name of an office, as at D. At the top of the bar is a scroll, E, and at the bottom thereof a scroll, F.

Pendent from the scroll F is a shield, G, which rests on the ribbon, and on the face of which is a monogram.

I claim—

- 25 1. A design for a badge having a bar with a scroll below the same and a shield pendent therefrom and a ribbon pendent from the bar, all substantially as shown.
- 30 2. A design for a badge having a bar with a scroll at top and bottom thereof and a shield pendent from said lower scroll, substantially as shown.
- 35 3. A design for a badge, consisting of a cross, a ribbon, a top bar, and a shield, the cross being pendent from the ribbon and the shield pendent from the bar to which the ribbon is attached, as shown and described.

JOS. K. DAVISON.
